United States Patent Office

Des. 218,151
Patented July 28, 1970

218,151

DISPENSING CONTAINER

Androus D. Noyes, Ossining, and Robert N. Marona,
Harrison, N.Y., assignors to Morton International, Inc.,
Chicago, Ill., a corporation of Delaware

Continuation of design applications Ser. No. 15,148 and
Ser. No. 15,153, both dated Dec. 30, 1968. This appli-
cation June 20, 1969, Ser. No. 17,789

Term of patent 14 years

Int. Cl. D9—01

U.S. Cl. D9—156

FIG. 1 is a perspective view of a dispensing container showing our new design;

FIG. 2 is an elevational view on an enlarged scale;

FIG. 3 is an elevational view looking from the right of FIG. 2;

FIG. 4 is a top plan view of FIG. 3;

FIG. 5 is a bottom plan view thereof;

FIG. 6 is a perspective view on the same scale as FIG. 1 but showing a modified form of our new design;

FIG. 7 is an elevational view thereof on an enlarged scale;

FIG. 8 is an elevational view looking from the right of FIG. 7;

FIG. 9 is a top plan view of FIG. 8; and

FIG. 10 is a bottom plan view thereof.

This application is a continuation of our applications Ser. Nos. D. 15,148 and D. 15,153, both filed Dec. 30, 1968.

We claim:

The ornamental design for a dispensing container, substantially as shown and described.
